(57) CLAIM

The ornamental design for a “lampshade,” as shown and described.

DESCRIPTION

FIG. 1 is a perspective view of a “lampshade” showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a perspective view showing the practical usage thereof; and,

FIG. 9 is a perspective view showing another practical usage thereof.

The broken line showing is included for the purpose of illustration and forms no part of the claimed design.
